UNITED STATES PATENT OFFICE

2,241,910

INTERNAL COMBUSTION ENGINE

Thomas E. Hull, Oakland, Calif.

Application April 16, 1940, Serial No. 329,899

6 Claims. (Cl. 123—63)

The invention relates to internal combustion engines and more particularly to the combustion chamber construction and fuel injection system of such engines.

An object of the invention is to provide an internal combustion engine of the character described wherein the fuel will be introduced into the combustion chamber of the engine during or at the end of the compression stroke of the engine and into a medium of hot quiescent compressed air and wherein the fuel is introduced in a rich hydroxylated air and fuel mixture whereby the admixture, distribution and burning of the fuel will be more uniform and with less tendency to detonate than in previous combustion engines, all cooperating to produce an increased efficiency and power output of the engine.

Another object of the invention is to provide an internal combustion engine of the character above which will effect a substantial simplification and reduction of number of parts and will effect a complete elimination of the usual electric ignition system of the common Otto cycle type engine.

A further object of the invention is to provide an internal combustion engine of the character above which readily lends itself to an opposed double-acting piston and cylinder type of construction affording a simplification and compactness of parts and a better balance and distribution of stresses in the engine.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a vertical cross-sectional view of an engine constructed in accordance with the present invention.

Figure 2 is a vertical cross-sectional view of the engine taken at substantially right angles to the plane of Figure 1 and as indicated by line 2—2 of Figure 1.

Figure 3 is a plan view of the engine with the top cover plate thereof removed.

Figure 4 is an enlarged vertical sectional view of the fuel injection passage and valve therein.

Figure 5 is a horizontal cross-sectional view of

the engine taken substantially on the plane of line 5—5 of Figure 1.

Figure 6 is a horizontal cross-sectional view taken substantially on the plane of line 6—6 of Figure 1.

Figure 7 is a vertical cross-sectional view of the several operating cams, each shown separately and in proper angular or circumferential relation.

Figure 8 is a vertical cross-sectional view of the passage and injector means similar to Figure 4 but showing a modified form of the invention.

The internal combustion engine of the present invention consists briefly of a relative reciprocating piston and cylinder unit defining an engine chamber of variable size for carrying out the expansion and compression strokes of an internal combustion engine cycle and into which chamber is periodically fed during or at the end of the compression stroke, a rich gaseous mixture of fuel and air or exhaust gas which is ignited upon admixture with the hot quiescent air in the chamber at the end of the compression stroke without the required assistance of a spark or other ignition means. The gaseous air and fuel mixture is preferably received and compressed and injected into the main engine chamber aforementioned by means of an auxiliary compressor unit operated jointly and in timed relation with the main engine piston and cylinder unit above.

With reference to the accompanying drawings, and more particularly to Figures 1 and 2, the internal combustion engine herein illustrated is of the opposed double acting piston and cylinder type, including upper and lower stationary pistons 11 and 12, which are arranged in longitudinal alignment and are embraced by cylindrical bores 13 and 14 provided in a casing member 16. A cross partition 17 in the member 16 separates the cylinders 13 and 14 and provides closed ends therein which cooperate with the heads 18 and 19 of the pistons to define engine chambers 21 and 22 which vary in size upon reciprocation of the member 16 to provide the expansion and compression strokes of an internal combustion engine. As will be clear from the type of structure here illustrated, the upper compartments 21 will be compressed while the lower compartment 22 is expanded and throughout the operating cycles of the two engine units the units will be 180° out of phase with each other, relative to crank shaft rotation. This out of phase relationship of the units and the direct longitudinal alignment of the compartments provides an improved balance and distribution of operating stresses as well as a

simplification and a reduction of parts providing the engine cylinders in a single sliding sleeve casing.

Valve and passage means is provided for each of the compartments 21 and 22 for introducing air into the compartments for compression and for exhausting the spent combustion products at the end of the power stroke. As an important feature in the present construction, such passage and valve means is incorporated directly in the pistons 11 and 12, whereby the valve and passage assembly and the several operating parts for the valve may be supported on a stationary part of the engine without interfering with the relative movement of the sleeve 16. As will be best seen from Figures 1, 2, 5 and 6, each of the pistons 11 and 12 is divided by a pair of transverse longitudinally extending interior walls 23 and 24 to define in conjunction with the side wall 26 of the piston a pair of spaced passages 21 and 28 for the exhaust and intake respectively of the gases. Defined between the walls 23 and 24 is a compartment 29 which in accordance with the present construction is operatively connected with the circulatory cooling system of the engine for circulating water, oil or other cooling medium through the piston. The passages 21 and 28 extend longitudinally to the heads 18 and 19 of the pistons and are there communicated with circular valve seats 31 and 32 which are engaged by exhaust and intake poppet valves 33 and 34. These valves are provided with stems 36 which extend through longitudinal openings or bores 37 in the piston and are normally drawn to a closed position against seats 31 and 32 by means of helical valve springs 38 which are compressed between a spring seat 39 on the free end of the stem and a spring seat 41 carried by the body portion of the piston.

In operation of the engine the exhaust and intake valves 33 and 34 of each of the engine units are open during one stroke, or 180°, of the cycle relative to crank shaft rotation in the conventional manner, whereby the intake valve is open during a suction stroke for the intake of air and is closed during the compression, power and exhaust strokes of the cycle, and the exhaust valve is open following the power stroke for the discharge of the spent combustion products for 180° of crank shaft rotation and is closed during the intake compression and power strokes. Means for so opening and closing these valves is here embodied in the form of a cam shaft 42 which is operatively connected to the crank shaft of the engine so as to rotate the cam shaft at one-half crank shaft speed. The cam shaft is here rotatably supported across the top of the piston 11 and carries cams 43 and 44 which bear directly upon the spring seats 39 at the upper ends of the stems of valves 33 and 34. The lower intake and exhaust valves 33 and 34 are operated by cams 46 and 47 mounted on the cam shaft 42 and operatively connected by rocker arms 48 and 49 with rods 51 and 52 which extend vertically exteriorly of the sleeve member 16 and are connected at their lower ends with rocker arms 53 and 54 which are carried on sleeves 56 and 57 on a shaft 58 journaled across the bottom of the lower piston and on which sleeves are secured to arms 59 and 61, which in turn engage the lower ends of spring rests 62 and 63 engaging the lower ends of stems of valves 33 and 34.

The sleeve member 16 is reciprocated relative to the stationary pistons 11 and 12 by means of

connecting rods 64 and 66 which are journaled on bearing pins 67 and 68 carried by the exterior of the sleeve member adjacent the partition 17 and which are operatively connected at their opposite ends to the crank shaft of the engine (not shown).

As explained above, the fuel is injected into the engine compartments 21 and 22 preferably in a rich gaseous air and fuel mixture during or adjacent the end of the compression stroke of the engine, whereby the rich gaseous fuel mixture is admixed with hot quiescent compressed air in the compartments for supporting combustion. In accordance with the present construction the rich fuel mixture is received and compressed and fed into the main engine chambers by means of auxiliary compressor units which are preferably of the piston and cylinder type. The fuel mixture is compressed in a rich state in the presence of an insufficient quantity of oxygen to support combustion. As here shown, with particular reference to Figure 1, I provide a pair of stationary pistons 69 and 71 adjacent and parallel to the pistons 11 and 12 and these auxiliary pistons are embraced by cylindrical bores 72 and 73 formed in the reciprocating sleeve member 16. As will be seen from Figure 1, the piston 69 is parallel to and is of approximately the same length as piston 11, whereas piston 71 is parallel to and approximately of the same length as piston 12 and pistons 69 and 71 are in longitudinal alignment. The chamber 74 is defined between the head end 76 of piston 69 and a partition portion 77 of the sleeve member separating the cylinders 72 and 73 and a similar compartment 78 is defined between the head end 79 of piston 71 and the partition 77. Upon reciprocation of the sleeve member 16, the compartment 74 will be compressed simultaneously with the compartment 21 and at the same time compartment 78 will be expanded simultaneously with the compartment 22. On the next succeeding stroke of the sleeve member the compression and expansion of the compartments will be reversed.

During the expansion stroke of each of chambers 74 and 78 corresponding with the intake stroke of chambers 21 and 22, a rich gaseous air and fuel mixture is drawn into the chamber and upon the following compression stroke of the chamber this mixture is compressed to a pressure somewhat higher than the pressure obtained in the adjacent chamber 21 or 22 at the end of its compression stroke and the mixture is caused to flow under this pressure differential from the auxiliary chamber into the main engine chamber. The flow of the air and fuel mixture from the chambers 74 and 78 to the cylinders 21 and 22 is dependent upon the relative pressures in the chambers. The flow is substantially confined to the end of the compression stroke due to rapid motion of the sleeve adjacent the central portion of its stroke and the following temperature rise and further pressure rise caused by the temperature rise.

The pistons 69 and 71 are formed with longitudinal interior passages 81 and 82 which are adapted for connection exteriorly of the engine to a source of gaseous air and fuel mixture. Such a source may be obtained from a carburetor or other fuel and air mixing mechanism. The opposite ends of the passages 81 and 82 terminate in circular valve seat openings 80 and 85 in the heads 76 and 79 of the pistons, and these openings are opened and closed by poppet type

valves 83 and 84 carried by the pistons. In operation, these valves are open during three of the four operating strokes and are closed during the compression stroke of the chambers 74 and 78 corresponding with the compression stroke of chambers 21 and 22. Thus on the intake stroke of the engine, air and fuel mixture is drawn into the chambers 74 and 78 which is compressed on the succeeding compression stroke for passing into the adjacent engine compartments. The opening and closing of the valves 83 and 84 is arranged to be effected in timed relation to the movement of the sleeve member 16, by operating these valves from cams 93 and 94 on the cam shaft 42. Cam 94 is positioned adjacent the right end of the cam shaft, with reference to Figure 2, and engages a rocker arm 96 carried by a sleeve 97 on an auxiliary shaft 98 paralleling the cam shaft 42. An arm 99 carried by the sleeve 97 engages the upper end of the stem of valve 83. Cam 93 is located adjacent the left end of cam shaft 42, with reference to Figure 2 and operates the lower fuel intake valve 84 through a chain of mechanism including a vertical thrust rod 101 and a rocker arm 102 carried on an auxiliary shaft 103 adjacent the bottom of the engine, as seen in Figure 1, and parallel to the auxiliary shaft 58.

The compressed mixture is conveyed from the auxiliary chambers into the adjacent engine chambers by way of passages formed in the partition member 71 which communicates the head end of the cylinders 12 and 13 with the head ends of cylinders 13 and 14. Injection nozzles 86 and 87 are mounted in these passages. One of these nozzles is illustrated in enlarged form in Figure 4 of the drawings, wherein it will be seen that the member 86 is provided over an interior portion of its length with an axial passage 88 which is connected by a side port 89 to the head end of the auxiliary cylinder and which discharges at its interior end 91 into the head end of the engine cylinder.

As an important feature of the present construction, and as aforementioned, the pressure generated in the auxiliary chambers 74 and 78 is somewhat greater than the pressure generated on the compression stroke of the compartments 21 and 22, so as to cause a gaseous flow from the auxiliary chambers into the main engine chambers. This is here effected by arranging the auxiliary cylinders and pistons with a larger compression ratio than the main engine and piston cylinders. As will be seen from Figure 1, this effect is here obtained by providing a greater clearance between the heads of pistons 11 and 12 and the end wall 17 than between the heads of pistons 69 and 71 with the end wall 77. The increased compression ratio in the auxiliary compartments 74 and 78 produces an increasing rise in pressure towards the end of the compression stroke whereby the majority of the compressed air and fuel mixture will pass into the engine chambers adjacent to the end of the compression stroke in such chambers, and thereby insuring ignition only adjacent the end of such compression strokes. Also preferably, the compression ratio of the main engine units is such that a self-ignition temperature will be reached only adjacent the ends of the compression stroke.

In order to obtain a uni-directional flow of gas from the auxiliary chambers into the main engine chambers, I prefer to incorporate a check valve 92 in the interior passage 88 of the nozzles 86 and 87 which will close the passage upon ig-

nition of the fuel in the main engine chamber.

The operation of the engine, as will be understood from the foregoing, may be summarized as follows. With reference to Figure 1 and assuming that chamber 21 is about to start its power stroke, chamber 22 is about to start its exhaust stroke. Accordingly the intake and exhaust valves in piston 11 are closed and the exhaust valve in piston 19 is open. As the sleeve moves downwardly, with reference to Figure 1, the gases in chamber 22 are exhausted through passage 27 and the gases in chamber 21 expanded during the power stroke of the engine. At the end of this downward stroke of the sleeve, the exhaust valve opens in the top compartment and the intake valve opens in the bottom compartment and the gases are exhausted from the upper compartment while air is introduced into the lower compartment. On the following down stroke of the sleeve, the intake valve opens in the top chamber to admit air while the air which was taken into the lower compartment during the preceding stroke is compressed. During this stroke the valve 84 in the auxiliary compartment 78 is seated and the fuel mixture is compressed in the chamber 78. The mixture thus compressed in chamber 78 is passed through the injection nozzle 86 into the chamber 22 and ignition takes place adjacent the end of the down stroke of the sleeve. The check valve 92 then closes in the passage 88 communicating the auxiliary and main engine chambers to hold the burning and pressure in the main chamber 22. During the following upward movement of the sleeve the power stroke takes place in the lower compartment 22, while the compression stroke takes place in the upper compartment 21. During three of these four strokes including the power stroke, the exhaust stroke and the intake stroke, valves 83 and 84 in the auxiliary compartments remain open, and these valves are closed during the compression stroke so as to cause a passage of mixture into the main engine cylinders, as above described. The several cams 43, 44, 46, 47, 93 and 94 are illustrated in their co-related positions in Figure 7. Inasmuch as the cam shaft is operated at one-half crank shaft speed, the lift portions of the intake and exhaust cams 43, 44, 46 and 47 cover 90° of rotation of the cam shaft, corresponding with 180° of rotation of the crank shaft. In the case of the cams 93, 94 for the fuel valves, the lift portions subtend approximately 270° of the cam periphery. The cams are illustrated in Figure 7 in their position at the end of the compression stroke in the upper compartment, and the end of the power stroke in the lower compartment. While the engine is here arranged for four cycle operation, it will of course be understood that the same may be arranged with equal facility for two cycle operation by merely changing the shape and speed of rotation of the series of cams, so as to provide an intake, compression, power and exhaust operation during each reciprocation of the sleeve.

An important feature of the device resides in the fact that at throttled speeds, the fuel injection is automatically delayed and combustion retarded as is desirable at slow speeds and starting. Throttling is preferably accomplished by use of a butterfly valve (not shown) in the fuel intake passages 81 and 82, so that when the throttle is partially closed, a partial vacuum will be drawn in the chambers 74 and 78 which will then contain only enough gaseous fuel to operate the engine at reduced speed. Consequently during

the compression stroke on the gases contained in chambers 14 and 18, the pressure will not be built up sufficiently to cause flow into the main engine cylinder until relatively late in the compression stroke.

The engine construction here illustrated utilizing the opposed piston and cylinder arrangement, provides many advantages in the reduction of parts necessary and in obtaining a better distribution of stresses within the engine. The majority of stress insofar as the sleeve is concerned, is at the mid portion thereof adjacent the cross partition and the bearing pins 67 and 68. Accordingly, I prefer to use a greater wall thickness at the central portion of the sleeve and reduce the wall thickness towards the opposite open ends of the sleeve.

As a modified form of the invention I may positively withhold the passage of compressed air and fuel mixture from the auxiliary chambers 14 and 18 into the main engine chambers 21 and 22 until adjacent the end of the compression stroke. This may be effected, as illustrated in Figure 8, by the provision of a spring pressed check valve 92' in the passage 88' provided in the nozzle member 86' and communicating the auxiliary and main engine chambers. As shown in Figure 8, a helical spring 104 is mounted ahead of the valve 88' for urging the latter to its seated position in the passage and the tension of the spring is fixed to prevent the opening of the valve until adjacent the end of the compression stroke.

I claim:

1. An internal combustion engine comprising, a plurality of stationary pistons, a plurality of cylindrical sleeve members reciprocally embracing said pistons, means for jointly reciprocating said cylinders longitudinally relative to said pistons for compressing and expanding a chamber defined between each of the heads of said pistons and closed ends of said cylinders, valve and passage means connected to one of said chambers and operated in timed relation with the change of volume thereof for introducing air into said chamber and venting spent combustion products therefrom, valve and passage means connected to the other of said chambers for introducing a rich gaseous fuel and air mixture into said second chamber for compression therein, said second chamber having a higher compression ratio than said first chamber, and passage means connecting said chambers for passing compressed mixture from said second chamber into said first chamber.

2. An internal combustion engine comprising, a pair of stationary pistons mounted in parallel relation to each other, a member formed with a pair of parallel cylindrical bores slidably embracing said pistons and defining chambers between the heads of said pistons and the inner ends of said bores, means for reciprocating said member relative to said pistons for varying the volume of said chambers, valve and passage means connected to one of said chambers and operated in timed relation with the movement of said member for introducing air into said chamber during an enlarging stroke thereof and sealing said chamber during a compression and power stroke thereof and venting spent combustion products from the chamber during a volume reducing stroke thereof, valve and passage means connected to the other of said chambers and operated in timed relation to the movement of said member for introducing a rich gaseous fuel and air mixture into said second chamber for compression of the mixture therein, said second chamber having a higher compression ratio than said first chamber, and passage means connecting said chambers for passing compressed mixture from said second chamber into compressed air into said first chamber.

3. An internal combustion engine comprising, a pair of stationary pistons mounted in parallel relation to each other, a member formed with a pair of parallel cylindrical bores slidably embracing said pistons and defining chambers between the heads of said pistons and the inner ends of said bores, means for reciprocating said member relative to said pistons for varying the volume of said chambers, valve and passage means connected to one of said chambers and operated in timed relation with the movement of said member for introducing air into said chamber during an enlarging stroke thereof and sealing said chamber during a compression and power stroke thereof and venting spent combustion products from the chamber during a volume reducing stroke thereof, valve and passage means connected to the other of said chambers and operated in timed relation to the movement of said member for introducing a rich gaseous fuel and air mixture into said second chamber for compression of the mixture therein, said second chamber having a higher compression ratio than said first chamber, and passage means connecting said chambers for passing compressed mixture from said second chamber into compressed air into said first chamber.

4. An internal combustion engine comprising, a pair of stationary pistons mounted in parallel relation to each other, a member formed with a pair of parallel cylindrical bores slidably embracing said pistons and defining chambers between the heads of said pistons and the inner ends of said bores, means for reciprocating said member relative to said pistons for varying the volume of said chambers, valve and passage means incorporated in one of said piston heads and communicating with the chamber defined thereby and operated in timed relation with the movement of said member for introducing air into said chamber during an enlarging stroke thereof and sealing said chamber during a compression and power stroke thereof and venting spent combustion products from the chamber during a volume reducing stroke thereof, valve and passage means incorporated with the other of said piston heads and registering with the chamber defined thereby and operated in timed relation to the movement of said member for introducing a rich gaseous fuel and air mixture into said second chamber for compression of the mixture therein, said second chamber having a higher compression ratio than said first chamber, and passage means connecting said chambers for passing compressed mixture from said second chamber into compressed air into said first chamber, and a check valve in said last named passage means providing a uni-directional flow of fluid from said second chamber to said first chamber.

5. An internal combustion engine comprising, a relative reciprocating piston and cylinder unit defining an engine chamber of variable size for carrying out the expansion and compression strokes of an internal combustion engine cycle, valve and passage means connected to said chamber and operated in timed relation with the change in volume of said chamber for introducing air into said chamber and venting

70

spent combustion products therefrom, a second relative reciprocating piston and cylinder unit defining a chamber of varying volume and operated in synchronism with said first unit, means for introducing a rich fuel and air mixture into said second chamber for compression of the mixture therein, said second chamber having a higher compression ratio than said first chamber, and valve and passage means connecting said chambers and operative to withhold compressed mixture in said second chamber until adjacent the end of the compression stroke of both of said chambers and then to pass compressed mixture from said second chamber into compressed air in said first chamber.

6. An internal combustion engine comprising, a relative reciprocating piston and cylinder unit defining an engine chamber of variable size for carrying out the expansion and compression strokes of an internal combustion engine cycle, 20 valve and passage means connected to said

chamber and operated in timed relation with the change in volume of said chamber for introducing air into said chamber and venting spent combustion products therefrom, a second 5 relative reciprocating piston and cylinder unit defining a chamber of varying volume and operated in synchronism with said first unit, means for introducing a rich fuel and air mixture into said second chamber for compression of the mixture therein, said second chamber having a higher compression ratio than said first chamber, passage means connecting said chambers for passing compressed mixture from said second chamber into compressed air in said first chamber, and a spring pressed check valve mounted 10 in said last named passage means for providing a uni-directional fluid flow from said second chamber to said first chamber and withholding such flow until approximately the end of the compression stroke.

THOMAS E. HULL.
